FIELD CONTROL DEVICE

Filed June 29, 1923

UNITED STATES PATENT OFFICE

RICHARD W. CARLISLE, OF WILKINSBURG, PENNSYLVANIA, ASSIGNOR TO WESTINGHOUSE ELECTRIC & MANUFACTURING COMPANY, A CORPORATION OF PENNSYLVANIA

FIELD CONTROL DEVICE

Application filed June 29, 1928. Serial No. 289,320.

My invention relates to field-control devices and particularly to arcing devices for high-voltage insulators.

One object of my invention is to provide a device of the above-indicated character that shall keep arcs away from the insulator independently of the magnetic fields set up by the arcs.

Another object of my invention is to protect the upper end of a series of superposed insulator disks or flanges against damage by arcs.

Another object of my invention is to provide a field or arc-control device that shall effectively control arcs of both low and high-current values.

Another object of my invention is to utilize convection, caused by the heat of an arc, in controlling the arc.

Another object of my invention is to provide an insulator arc-control device that shall cause the arc to climb upwardly and away from the insulator.

Another object of my invention is to provide an arcing horn that shall have curved portions of such radius as to reduce corona to substantially a minimum.

A further object of my invention is to provide a field-control device that shall be simple and durable in construction, economical to manufacture and effective in its operation.

In high-voltage transmission-line insulators, particularly of the so-called series-string suspension type, protection against arcs for the upper ends thereof has been attempted by horns and rings of various types, all of which, to the best of my knowledge, either extend merely laterally or laterally and downwardly, none of them extending both upwardly and then downwardly in accordance with my invention hereinafter set forth.

In the former structures, with the highest part of the upper horn or radial ring support near the insulator and with an arc of relatively small current value, the hot gases of the arc tend to rise by convection, carrying the arc upwardly and inwardly to a po-

sition where damage may be done to the insulating material.

These small-current arcs do not induce sufficient magnetic field to offset the convection caused by the heat of the arc, and the device is, therefore, useless for protection against damage of this character.

Arcing rings may be somewhat less subject to the above-described fault than are arcing horns but the rings have another disadvantage in the relative cost thereof.

When the arc-current value is relatively high, the horn and arc form a current path the magnetic field of which forces the arc away from the insulator.

It is my aim to overcome the disadvantage of former arc or field-control devices, as above outlined, and, accordingly, I provide a device in which one of the terminals is so constructed as to keep the arcs away from the insulator, whether these arcs have relatively high or relatively low current values.

Figure 1 of the accompanying drawings is a top plan view of a field-control device constructed in accordance with my invention.

Fig. 2 is a longitudinal side elevational view of the device shown in Fig. 1, and

Fig. 3 is a view, similar to Fig. 2, of a modified form of my invention.

Referring to Figs. 1 and 2, the device comprises, in general, an insulator 2, a bottom clamp device 3 for supporting a transmission-line conductor 4 and upper and lower arcing-horns or field-control terminals 5 and 6, respectively.

The insulator 2 may be of any suitable type, being here depicted, for purposes of illustration, as of a usual series-string type embodying a plurality of flexibly connected units each comprising a dielectric body having a laterally-extending disk or petticoat 8, a metal cap 9 and an inner metal pin 10.

Each pin 10 is provided with an eye for connection, by a transverse pin 12, to a clevis 14 on the cap of the next lower unit or to the clamp 3, and the top clevis 14 is for attachment to a main supporting cross arm of a pole or tower (not shown).

The lower field-control device 6 may be of another shape but is preferably formed from

a single metal strap or bar having a central portion 15 secured in position by bolts 16, which also clamp the conductor 4 in the clamp 3, and upwardly and outwardly projecting portions 17 terminating in gradually-curved outer-end portions 18.

As indicated more clearly in Fig. 2, by reason of the central location of the portion 15 of the lower terminal 6 beneath the clamp 3 and the central location of the portions 18 over the conductor 4, portions 19 thereof curve laterally from the mid portion 15 and back again to the portion 17 around the conductor 4.

The upper terminal member 5, to which my invention more particularly relates, comprises rod or bar members 21 and 22 projecting laterally from the insulator and each having an inner end 23 disposed at one side and inwardly beyond the inner end of the other, adjacent to which ends, complementary curved or clamping portions 24 fit the upper cap 9 and are held in position by bolts 25. This construction provides a simple two-piece horn structure which facilitates manufacture and installation and reduces the clamping parts to substantially a minimum.

Each bar 22, from a position adjacent to the top cap 9, has a gradually bent or upwardly extending portion 27 merging into a gradually return-bent top portion 28 and, from the portion 28, into a downwardly and outwardly sloping portion 29, and a gradually upwardly curved end or tip 30 which lies below the clamping portion 24 of the bar.

In operation, upon discharge and with a small arc-current value, the arc rises by convection so that its upper end plays back and forth in the region of the upper bend 28. This action keeps the arc free of the top disk or petticoat 8 to prevent damage thereto.

With a discharge or arc current of relatively high value, the magnetic field, caused thereby in the arc and horns, forces the arc outwardly along the portion 29 to the tip 30, during which travel, or after reaching a position between the tips 30 and 18, it is extinguished or dissipated.

The bends in the horns are of such radius as to reduce the formation of corona thereon.

In the modification of my invention illustrated in Fig. 3, in which corresponding parts are designated by corresponding reference characters, the construction and operation are substantially the same as in the structure above described.

However, in this form, in which the device is shown as a dead-end insulator, the insulator may lie, in general, in a diagonal or substantially horizontal position, in which case, the horns at lower side of the longitudinal axis thereof may be omitted. This structure causes the arcs to operate between the upper horns substantially as above de-

scribed, since, when the weak-current arc strikes near the portion 27, it is carried by convection toward the portion 28, and the magnetic field of a strong-current arc, assisted by convection in this case, forces it upwardly or outwardly from the insulator, as in the first form.

In the above-described structure, in which the parts are substantially no greater in magnitude or number, no more difficult or expensive to manufacture or install and no more complicated than prior-art structures, a device is obtained, by simple means, which is of materially more effective operation than many of the devices heretofore employed.

While I have shown and described particular forms of my invention, changes may be effected therein without departing from the spirit and scope thereof, as set forth in the appended claims.

I claim as my invention:

1. An electrostatic - field - control device comprising spaced electrodes one of which has an inner portion adjacent to the longitudinal axis of the device, a portion extending from said inner portion to a position laterally at one side, and longitudinally removed from, said inner portion in a direction away from the other electrode and a portion extending from said position toward said other electrode to a position longitudinally spaced from said other electrode.

2. An electrostatic - field - control device comprising spaced electrodes one of which has an inner portion adjacent to the longitudinal axis of the device, a portion extending from said inner portion to a position laterally at one side, and longitudinally removed from, said inner portion in a direction away from the other electrode and a portion extending from said position toward said other electrode to a position longitudinally closer to said other terminal than said inner portion but longitudinally spaced from said other electrode.

3. In combination with an insulator, upper and lower electrodes, the upper electrode having an inner portion adjacent to the longitudinal axis of the insulator, a portion extending upward from said inner portion, a portion extending downward from said upwardly-extending portion and an outer-end portion below said inner portion and above the lower electrode, the upper portion of the upper electrode carrying the arcs during relatively low-current discharges and said end carrying the arcs during relatively high-current discharges.

4. In combination with an insulator, upper and lower electrodes, the upper electrode having an inner portion adjacent to the longitudinal axis of the insulator, a portion extending upward from said inner portion, a portion extending downward from said upwardly-extending portion and an outer-

end portion below said inner portion and above the lower electrode, the upper portion of the upper electrode carrying the arcs during relatively low-current discharges and said end carrying the arcs during relatively high-current discharges, the lower electrode having a portion extending upwardly at one side of the insulator.

5. In combination with an insulator, an upper arcing horn comprising a single integral metal member having an inner portion secured to the insulator adjacent to the longitudinal axis thereof, a portion gradually curved upwardly from said inner portion, 10 said upwardly-bent portion having a top gradual return-bend portion and a portion extending downwardly and outwardly from said top portion to a position below said inner portion.

20 6. In combination with an insulator, an upper arcing horn comprising a single integral metal member having an inner portion secured to the insulator adjacent to the longitudinal axis thereof, a portion gradually 25 curved upwardly from said inner portion, said upwardly-bent portion having a top gradual return-bend portion, a portion extending downwardly and outwardly from said top portion to a position below said inner 30 portion and an outer end portion curving gradually upwardly from said downwardly-extending portion.

7. An electrostatic - field - control device comprising spaced electrodes one of which 35 has an inner portion adjacent to the longitudinal axis of the device, an intermediate portion extending from said inner portion away from said other electrode and an outer portion extending from said intermediate portion toward said other electrode to a position longitudinally removed therefrom.

8. An electrostatic - field - control device comprising spaced electrodes one of which has an inner portion adjacent to the longitudinal 45 axis of the device, an intermediate portion extending from said inner portion away from said other electrode and an outer portion extending from said intermediate portion toward said other electrode to a position 50 longitudinally removed therefrom, there being rounded portions between said inner and intermediate portions, between said intermediate and outer portions and at the outer end of said outer portion.

55 9. In combination with an insulator, electrodes spaced relative to each other in the direction of the longitudinal axis of the insulator and one of which has a portion laterally spaced from the insulator to cause an arc 60 between the electrodes to extend in the general direction substantially parallel to said axis and to strike said portion free from the insulator, a second portion extending from said first portion and away from the other 65 electrode and a third portion extending

from said second portion toward said other electrode.

10. In combination with an insulator, electrodes spaced relative to each other in the direction of the longitudinal axis of the insulator and one of which has a portion laterally spaced from the insulator to cause an arc 70 between the electrodes to extend in the general direction substantially parallel to said axis and to strike said portion free from the insulator, a second portion extending from said first portion and away from the other electrode and a third portion extending from said second portion toward said other electrode to a fourth portion that is closer to the 75 other electrode than said laterally-spaced portion.

In testimony whereof, I have hereunto subscribed my name this 20th day of June, 1928.
